TOOL DISPLAY RACK OR SIMILAR ARTICLE

Ben J. Krueger, Chicago, Ill., and John T. Mains, Columbus, Ohio, assignors to The Union Fork and Hoe Company, Columbus, Ohio, a corporation of Ohio

Application November 27, 1956, Serial No. 43,956

Term of patent 14 years

(Cl. D80—9)

FIG. 1.

FIG. 2.

FIG. 3.

Fig. 1 is a perspective view of a tool display rack or similar article showing our new design;

Fig. 2 is a top plan view; and

Fig. 3 is an end elevational view thereof.

We claim:

The ornamental design for a tool display rack or similar article, substantially as shown.
